2,383,260

TYPEWRITING MACHINE

John Joseph Kittel, St. Albans, N. Y., assignor to
 Royal Typewriter Company, Inc., New York,
 N. Y., a corporation of New York

Original application July 3, 1943, Serial No.
 493,450. Divided and this application March 4,
 1944, Serial No. 525,060

2 Claims. (Cl. 197—107)

This invention relates to typewriting or like machines, and more particularly to means for preventing operation of mechanism for actuating a type bar or other printing member when associated mechanism for actuating a companion type bar or printing member is in operation.

This application is a division of my copending application Serial Number 493,450, filed July 3, 1943.

An object of the invention is to provide improved mechanism for preventing operative depressing of more than one key lever or other typing instrumentality at the same time so as to make it impossible for two or more type bars or other printing members to collide and/or jam.

Another object of the invention is to provide mechanism of the character stated in which a key lever blocking device is adapted to be operated by line lock mechanism but in which operation of the blocking device does not affect the line lock mechanism.

Other objects will become apparent from a reading of the following detailed description, the appended claims, and the accompanying drawing in which:

Figure 1 is a fragmentary vertical, fore and aft section of a typewriter mechanism embodying the invention;

Figure 2 is a fragmentary detail elevation of a safety lock mechanism embodying the invention drawn on an enlarged scale; and

Figure 3 is a fragmentary horizontal section on the line 3—3 of Figure 1.

The invention is capable of being embodied in typewriting machines of various kinds. For the purposes of illustration it is shown in connection with a typewriter the general construction and arrangement of many of the parts of which conform to the well known Royal Standard typewriter construction.

The typewriter illustrated comprises a main frame A on which a carriage B equipped with a platen C is mounted for letter spacing and return movements.

When the machine is conditioned for operation, the carriage B is urged to move in the letter spacing direction under the control of an escapement mechanism unit generally designated D. The escapement mechanism comprises a fixed frame 6 which pivotally mounts a rocker 7 carrying a fixed dog 8 and a pivoted dog 9 cooperable in the usual manner with an escapement wheel 10. The wheel 10 is connected through a pawl 10^a to a pinion 11 normally in mesh with an escapement rack 12 mounted on the carriage.

5 A universal frame 13 includes arms one of which is shown at 14 pivoted at 15 on a frame mounted bracket 16. The universal frame is urged rearwardly by a spring 17 and includes a universal bar 18 adapted to be pulled forwardly upon the depression of one of the usual key levers or the space bar. Adjustably mounted on the frame 13 is a pressure plate 19 adapted to push against a roller 20 journaled at the lower end of a spring 10 arm 21 carried by the rocker 7. When the frame 13 is rocked clockwise as viewed in Figure 1, the plate 19 pushes the roller 20 so as to rock the rocker 7 and operate the escapement mechanism D to effect a single letter spacing movement of the carriage in the usual manner. The usual space bar (not shown) having the arms 21^a is connected by a link 21^b to the universal frame 13.

15 The escapement rack 12 is mounted on a bail 22 which is pivoted as at 23 on the carriage end plates one of which is shown at 24. Springs (not shown) respectively interposed between the carriage end plates and rearwardly extending arms integral with the bail 22 normally hold the rack 12 down in engagement with the escapement pinion 11. For permitting tabulating movements of the carriage B, the bail 22 and the rack 12 are rocked clockwise as viewed in Figure 1 by a tabulating rack lift lever pivoted on the main frame and being formed with an ear 30 engageable with the bail 22 in the usual manner.

20 The travel of the carriage in letter spacing and return directions is limited respectively by margin stops mounted on a margin stop bar 38 and being cooperable with a center stop 39. The right hand margin stop is shown at 36 in Figure 1. When the carriage approaches the end of its travel to the left in the letter spacing direction, the margin stop 36 operates a line lock lever 40 so that when the carriage is brought to rest by the center stop 39 the key levers cannot be operated. The line lock lever 40 is pivoted as at 41 on the center stop 39 and is formed with a downwardly extending arm 42, the lower end of which is connected by a link 43 to one arm 44 of a lever 45 pivoted as at 46 on frame brackets 47. A spring 48 interposed between the lever arm 44 and a frame mounted ear 49 biases or urges the lever 45 and line lock lever 40 to non-line locking position, movement of the parts under the urge of the spring 48 being limited by engagement of a stop projection 50 on the lever 45 with the frame A. Another arm 44^a of the lever 45 is connected by a link 51 to a key lever blocking device, which in the form shown comprises a line lock plate 52 pivoted as at 53.

The usual case shift member, in the form shown a type bar segment E, is mounted for vertical shifting on the frame A and is equipped with a pivot wire 54 which mounts the usual complement of type bar members, one of which is shown at 55. Each type member 55 is formed with a short arm 56 connected by a link 57 to an intermediate lever 58 pivoted as at 59 on the key lever bracket 60 carried by the frame A. The bracket 60 also mounts the key levers 61 which are pivoted on a fulcrum shaft 62 and are urged upwardly against a stop 63 by returning springs 64. Each key device 61 is connected by a link 65 to a front lever 66 pivoted as at 67 on the frame A. The type bars 55 normally and when in inactive position are supported at their free ends by a head rest 68.

In the conventional Royal Standard construction, as for example the construction shown in the patent to Henry J. Hart, No. 2,202,451, granted May 28, 1940, each of the front levers corresponding to the lever 66 shown in Figure 1 is connected by a link to an associated intermediate lever corresponding to the lever 58 shown in Figure 1 so that upon depression of a key lever, manually applied force is transmitted to the type bar for moving it to printing position. The invention claimed herein may be embodied either in typewriters in which manually applied force is relied upon for actuating the type bars, or in typewriters in which depression of a key lever controls the action of power means which applies the actual force for moving the type bars to printing position. In the illustrative embodiment depression of a key lever is utilized to disable a restraining device so as to permit power operable means to apply the effort for moving the associated type bar.

It will be understood that a key lever 61, the type bar 55 and associated parts shown in the drawings are representative of each of the plurality of type bar actions and associated key mechanism although only one complete type bar action is shown. The description of one complete type bar action is intended to serve as a description of the other type bar actions.

The carriage B may be urged in the letter spacing direction by any suitable means, for example by the usual spring barrel motor or by mechanism disclosed in the parent application Serial Number 493,450 referred to above, and disclosed and claimed in the co-pending divisional application Serial Number 525,058, filed March 4, 1944. In this mechanism a gear, a portion of which is shown at 106, constantly urges a carriage drive rack 108 to move the carriage in the letter spacing direction. The carriage is connected to a cam shaft 169 by gearing not shown herein but fully disclosed in the copending applications referred to. The arrangement is such that for each letter spacing movement of the carriage the cam shaft 169 turns through one eighth of a complete revolution.

The mechanism for operating and for controlling the operation of the type bars 55 is claimed in the parent application Serial Number 493,450 and is similar in some respects to mechanism disclosed in the copending application of John J. Kittel, Serial No. 493,449, filed July 3, 1943. Depressing of a key lever 61 is not made effective for applying manually exerted force for moving the type bar 55 on its printing stroke, but is utilized for releasing the restraint on a spring 79 connected between the intermediate lever 58 and an adjusting plate 157 pivoted as

at 158 on the frame A. When released, the spring 79 contracts and rocks the lever 58 counterclockwise, thereby swinging the type bar 55 to printing position.

Depending from a curved slot 159 in the lever 58 is a link 160 pivoted at its lower end to a cam follower lever 161 in turn pivoted as at 162 on the frame A. The lever 161 is equipped with an anti-friction roller 163 which normally is held against upward movement by the restraining face 164 of a releasable bar lock keeper 165 pivoted as at 166. The roller 163 also is releasably restrained against upward movement by the crest of one of the eight lobes 167 on a resetting member comprising a cam 168 secured to the shaft 169. Normally the cam 168 is positioned with the crest of a lobe 167 directly above the roller 163. Thus, both the bar lock keeper 165 and the cam 168 normally prevent rising of the roller 163 and therefore normally restrain the lever 58 from being rocked by the spring 79. In order to discontinue the restraint of both the keeper 165 and the resetting member 168 and permit the spring 79 to contract and drive the type bar to printing position it is necessary to displace the restraining face 164 of the keeper 165 from above the roller 163 and also to rotate the cam 168 so as to allow the roller to move into the depression between two cam lobes 167.

The bar lock keeper 165 is adapted to be rocked upon depression of the associated key 61 for displacing the restraining face 164 from above the roller 163. For this purpose an arm 178 on the keeper 165 is connected by a link 178^a to the key operated lever 66. Thus, upon depression of the key 61, the link 65 will rock the lever 66 clockwise to pull on the link 178^a and rock the keeper 165 counterclockwise thereby moving the keeper face 164 away from the roller 163.

Thereafter, to enable the spring 79 to actuate the lever 58, link 57 and type bar 55, the cam 168 is rotated one-eighth of a revolution. While the depression between the lobe 167 last positioned above the roller 163 and the next adjacent lobe is presented above the roller the lever 161 is free to rock clockwise. Hence the spring 79 contracts and rocks the intermediate lever 58 counterclockwise unrestrained by the link 160 and lever 161, and the link 57 is pulled forwardly to swing the type bar 55 to printing position, as shown in Figure 1.

The force of the type bar printing impact may be varied by turning an adjusting screw 179 carried by the adjusting plate 157 and having its end engaging a fixed part of the frame A. If the screw 179 is turned to rock the adjusting plate 157 clockwise as viewed in Figure 1, the springs 79 associated with the respective type bars will be subjected to additional tension so as to be capable of swinging the type bars 55 into printing position with more force. Adjustment of the tension of the springs 79 is accompanied by a variation in the force required to depress the key levers 61, thus requiring a heavier "touch" to effect operation of a type bar. This is because additional tensioning of the springs 79 causes the rollers 163 to be held against the keepers 165 with greater force, thereby requiring additional manually applied effort for moving the keepers 165 from engagement with the rollers 163.

For operating the escapement mechanism D in response to the depression of a key lever 61, a supplemental universal bar 180 is pivoted at 166 and is engaged by projections 181 formed respec-

tively on the bar keepers 165. An arm 182 on the supplemental universal bar 180 is connected to the escapement frame 13 by a pull rod 183 having its rear end hooked at 184 to embrace the rod 18 on the universal frame 13. Thus, when a key lever 61 is depressed, the associated keeper 165 is swung counterclockwise to the position shown in Figure 1, thereby rocking the supplemental universal bar 180 counterclockwise and swinging the universal frame 13 clockwise to actuate the escapement mechanism. When the key lever is released, the springs 17 and 64 will contract to restore the parts to their positions.

Normally each type bar actuating spring 79 is restrained by engagement of the associated roller 163 with a lobe 167 and with the associated keeper restraining face 164. When a key lever 61 is depressed, the associated keeper 165 is swung to the position shown in Figure 1, thereby rocking the supplemental universal bar 180 and operating the escapement mechanism D in the manner previously described. When the carriage moves in response to operation of the escapement mechanism the cam shaft 169 is rotated as explained above. As the cam lobe 167 which was in contact with the roller 163 prior to operation of the key lever 61 moves from above the roller 163, a cam depression will be presented above the roller 163 and the roller will be enabled to rise so as to permit the spring 79 to move the type bar 55 to printing position, the retreating cam lobe piloting the type bar to typing position. The type bar will reach printing position when the cam shaft has moved through one-sixteenth of a revolution, the parts then being positioned as shown in Figure 1. During the next one-sixteenth of a revolution of the cam shaft 169, the next or following cam lobe 167 will engage the roller 163 so as to move the arm 161 downwardly, thereby restoring the type bar 55 to its position of rest, reloading the spring 79, and enabling the restraining face 164 of the keeper 165 to move over the roller 163. The parts will then have been returned to their normal positions and the escapement mechanism D will have arrested the carriage and the cam shaft 169.

As shown in Figure 1, the shape and size of the cam 168, the mounting of the type member 55, and the connections between the roller 163 and the type member 55 are so interrelated that the roller 163 is out of contact with the cam 168 when the type member 55 reaches typing position. Thus the cam 168 is effective for restraining or piloting the type member during part of the typing stroke but not during the last part of the stroke. Consequently the adjustment of the spring 79 can be effective for varying the force of the type impact.

Safety lock mechanism

Means are provided for preventing operative depressing of a key lever 61 before a previously depressed key lever has returned to its normal position. In the form shown, the usual Royal line lock plate 52 is modified by having formed integrally therewith an extension blade 332 which serves as an operating part adapted to be engaged by the heel 333 of an abutment 334 on any key lever 61 when it is depressed. The device comprising the parts 52 and 332 is generally of V

shape with the leg 332 normally extending diagonally across the paths of the abutment heels 333. When the key lever is depressed the abutment heel 333 engages the operating part

- 6 332 and rocks the blocking part 52 rearwardly from its normal forwardly offset position to the position shown in full lines in Figure 2. The line lock plate 52 will then be disposed directly under the toes 335 of the aligned key lever abutments 334 so as to prevent operative downward movement of the other key levers. This operation of the safety lock does not disturb the line lock lever 40 because the link 51 interposed between the line lock plate 52 and the line lock lever 40 has its front end connected to the line lock plate 52 by a one way drive connection including a part 336 of the link 51 and a slot 337 in the line lock plate. Thus rearward movement of the link 51 in response to operation of the line lock lever 40 will move the line lock plate 52 to its locking position but rearward movement of the line locking plate caused by depression of a key lever 61 will not move the link 51.

The mechanism described with reference to the drawings embodies the invention in the form now preferred, but it is evident that changes may be made without departing from the invention as defined in the claims.

I claim:

- 30 1. In a typewriter or like machine, a plurality of type members; means including a plurality of key levers associated respectively with said type members for effecting selective operation of said type members; aligned abutments on said key 35 levers, each including a heel and a toe spaced horizontally from said heel and at substantially the same level therewith; a blocking device; and means pivoting said device to rock about an axis parallel to the direction of alignment of said 40 abutments, said device comprising a blocking part positioned out of the paths of said abutment toes when said device is in normal position and an operating part formed integrally with the blocking part and normally being disposed in the paths of said abutment heels and being engageable by the abutment heels on an operated key lever for rocking said device to position said blocking part thereof in the paths of the other abutment toes.
- 50 2. In a typewriter or like machine, a plurality of type members; means including a plurality of key levers associated respectively with said type members for effecting selective operation of said type members; aligned abutments on said key 55 levers respectively, each including a heel and a toe spaced horizontally from said heel and at substantially the same level therewith; a blocking device; and means pivoting said abutment to rock about an axis parallel to the direction of alignment of said abutments, said device being generally V shaped in cross section and including a blocking leg normally disposed laterally offset from the paths of said abutment toes and an operating leg, formed integrally with the blocking leg and extending diagonally across the paths of said abutment heels and being engageable by the abutment heel of any operated key lever for rocking said device to position said blocking leg in the paths of the abutment toes.
- 60 70 JOHN JOSEPH KITTEL.
